CARBON INTERLEAVED RECORD ASSEMBLY

Joseph A. Gilbert, San Francisco, Calif., assignor
to Moore Business Forms, Inc., a corporation of
Delaware

Application November 21, 1944, Serial No. 564,445

7 Claims. (CL. 282—8)

1

This invention relates to improvements in manifolding assemblies embodying a plurality of record and transfer leaves attached together to form a unitary assembly. The invention relates more particularly to manifolding assemblies of this nature wherein an improved arrangement is provided for quickly and easily effecting selective separation of the record and transfer leaves following entry of the transfer inscriptions.

It is a general object of the invention to provide in a manifolding assembly of the class mentioned, an improved manner of attaching the record and transfer sheets together so that they can be quickly and easily separated following transfer inscription thereof, and whereby an additional record leaf sometimes known as a ledger sheet, can be assembled or collated in transfer relation with the other assembly leaves while avoiding incorrect interleaving of the ledger sheet and consequent errors in the inscriptions.

Another object of the invention is to provide an improved attaching arrangement for attaching the record and transfer leaves in manifolding assemblies, so as to provide means for assuring the positioning of the ledger sheet in its correct position for receiving transfer inscriptions, thus avoiding errors and inaccuracies in the inscriptions made on the various record leaves of the assembly.

A further object of the invention is to provide for manifolding assemblies of the class mentioned, an improved selective grip arrangement or selective separating means for facilitating selective separation of the record and transfer leaves of the assembly.

According to a particular feature of improvement of this invention, a plurality of record leaves are attached along one margin thereof by sheet folds or other means of attachment, the attached record leaves having opposite free marginal portions to which transfer leaves are respectively independently attached and supported in interleaved transfer relation in the assembly.

Other objects and advantages of the invention will be in part pointed out in the following detailed disclosure of certain illustrative but preferred embodiments of the invention, and will be in part obvious as the disclosure proceeds.

The invention accordingly comprises the features of construction, combination of elements, and arrangement of parts, which will be exemplified in the construction hereinafter set forth and the scope of the application of which will be indicated in the claims.

For a more complete disclosure of the nature,

2

objects and advantages of the invention, reference is had to the following detailed description of the illustrative embodiments, and to the accompanying drawings in which:

- 5 Fig. 1 is a perspective view of a manifolding assembly embodying the invention, the leaves of the assembly being shown as slightly separated, and parts being broken away so as to improve the disclosure;
- 10 Fig. 2 is a plan view showing the assembly opened out or unfolded so as to show the construction and arrangement of the record and transfer leaves, parts being broken away to show the structure more clearly;
- 15 Fig. 3 is a partially diagrammatic end view of the assembly shown in Fig. 1;
- 20 Fig. 4 is a perspective view similar to Fig. 1 but showing a modified embodiment of the assembly;
- 25 Fig. 5 is a plan view similar to that of Fig. 2 but showing the modified embodiment of Fig. 4;
- 30 Fig. 6 is a fragmentary perspective view similar to the views of Figs. 1 and 4 but showing a further modified construction;
- 35 Fig. 7 is a plan view similar to Fig. 2 but on a smaller scale and showing the modified embodiment of Fig. 6; and
- 40 Fig. 8 is a fragmentary partially diagrammatic end view similar to Fig. 3 but showing the embodiment of Fig. 6.
- 45 Referring to the drawing for a detailed description of the illustrative embodiments there shown, and first to the preferred embodiment of Figs. 1, 2 and 3, the improved manifolding assembly embodies a record sheet A of paper or similar material and of sufficient length to form two record sheets, including an original record leaf 1 and a copy record leaf 2. The assembly also has a carbon or transfer sheet B substantially the same size and shape as the record sheet A. The record sheet A and transfer sheet B are arranged in superposed relation, as best seen in Fig. 2, and are attached together at their opposite longitudinal extremities as, for example, by marginal lines of adhesive 3 interposed between the adjacent sheet surfaces, although other well known forms of attaching means may be used when desired. Approximately one-half of the transfer sheet B at the left in Fig. 2 is coated with carbon or similar transfer material 4 on one side of the sheet, while the other half of the transfer sheet is similarly coated with transfer material 5 at the opposite side of the sheet. In effect, this arrangement provides two transfer leaves 6 and 7, as later more fully described.
- 50 55 The record sheet A and transfer sheet B at-

tached together as described are folded along transverse lines 8 and 9 so as to bring the record and transfer leaves in superposed transfer relation, as shown in Fig. 1. The fold line 8 of the record sheet is preferably weakened as by perforating, scoring, slitting, or the like, so that the record leaves 1 and 2 attached at this fold line can be quickly and easily severed from each other. When the record and transfer sheets are thus folded, the fold 9 of the transfer sheet is substantially enclosed within the fold of the record sheet. Also, when thus folded it will be seen that the transfer surface 4 of the transfer leaf 6 and the transfer surface 5 of the transfer leaf 7 are both directed downwardly so that transfer inscriptions entered upon the blank form 10 of the original record leaf will be transferred to underlying record receiving surfaces. The copy record leaf 2 may also be provided with a blank form similar to the blank form 10 and arranged in aligned transfer relation with the latter.

When the record sheet A and transfer sheet B are attached together and folded as described, it will be noted that the free marginal portions of the record leaves, or those opposite to the folds 8 and 9, are free from attachment with each other but that these margins are individually attached to the adjacent margins of the transfer leaves so as to support the latter in transfer relation in the assembly. There is no attachment between these free margins of the original record leaf 1 and the copy record leaf 2. Thus, by means of this arrangement, an unobstructed passageway is provided between the upper and lower record sheets at the end or edge of the assembly through which an additional record leaf or ledger sheet C can be entered and collated in transfer relation with the other assembly leaves, as later more fully described.

Extending along the free marginal portion of the record leaf 1 is a weakened severance line 11 formed by perforating, scoring, slitting, or the like, and a similar weakened severance line 12 is positioned along the free marginal portion of the copy record leaf 2. When the assembly is in its normal folded condition, as shown in Fig. 1, these weakened severance lines 11 and 12 will be in substantially superposed relation. Thus, a detachable binding stub 13 is provided at the free marginal portion of the original record leaf and attached in supporting relation with the adjacent marginal portion of the transfer leaf 6, while a similar detachable binding stub 14 relatively superposed with the other stub is provided at the free marginal portion of the copy record leaf 2, attached in supporting relation with the adjacent margin of the transfer leaf 7. It will thus be seen that there are no loose or unsupported marginal portions of the transfer leaves adjacent to the free margins of the record leaves.

The transfer sheet B, as best seen in Fig. 2, is provided with a deep marginal notch 15 adjacent to the fold line 9 and extending to opposite sides of this line. Thus, when the assembly is in normal folded condition, as shown in Fig. 1, this notch 15 provides a selective grip formation whereby the adjacent aligned marginal portions of the record leaves can be engaged or gripped without at the same time gripping the transfer leaves. This selective grip formation serves as a selective separating means for separating the record and transfer leaves from each other following a transfer inscription of the assembly, as more fully described below.

Also, as best seen in Fig. 2, weakened severance lines 16 are provided in the carbon leaves 6 and 7, each spaced slightly from the fold line 9 and forming narrow detachable strips or sections 17 which may serve as selective separating means for the record and transfer leaves to be used instead of the selective grip formations provided by the notches 15. The selective means provided by the narrow detachable strips 17 is described more fully in connection with the modified embodiment, as shown in Figs. 4 and 5.

The ledger sheet or loose record sheet C may be made of record paper similar to that of the record leaves 1 and 2 or it may be made of slightly heavier paper, and it is ordinarily provided on its upper or inscription receiving surface with a blank form similar to the blank form 10 which is aligned in inscription receiving relation with the latter form when the ledger sheet is inserted into its normal operative position, as shown in Fig. 1. This loose ledger sheet is sized and proportioned so that its outer margin, or that at the right in Fig. 1, will project slightly beyond the adjacent edge of the original record leaf 1 when in operative transfer position so as to be accessible for removal. The folds 8, 9 serve as a stop to position the ledger sheet in its operative position.

In use the improved manifolding assembly can be readily inserted for inscription in a typewriter or other writing machine, or the inscriptions can be entered manually by a pencil or the like. If a ledger sheet C is not already interleaved in transfer position, as shown in Fig. 1, it can be quickly and easily collated with the other assembly leaves without any danger of getting it in the wrong position so that the inscriptions would be improperly entered. This is for the reason that the entrance passageway for the ledger sheet is entirely free from adjacent loose edges of transfer leaves, the adjacent edges of the transfer leaves 6 and 7 being attached to the adjacent overlying and underlying marginal portions of the record leaves 1 and 2. The only place for inserting the ledger sheet is between the upper and lower attached edges of the transfer leaves 6 and 7, and it is therefore impossible to insert the ledger sheet except in its correct transfer relation between the two adjacent transfer leaves. Insertion of the ledger sheet is additionally facilitated by extending the lower binding stub 14 with its attached transfer leaf 7 slightly beyond the outer edge of the upper leaves 1 and 6. This outwardly extending portion of the two lower leaves thus provides a guide for directing the ledger sheet into the entrance passageway to the assembly.

When the inscriptions are entered on the original record leaf 1 of the assembly, transfer inscriptions are made upon the upper surfaces of the ledger sheet C and the copy record leaf 2 by means of the transfer leaves. After entry of the inscriptions the loose ledger sheet is ordinarily removed before separation of the record and transfer leaves. Then the inscribed record leaves and the transfer leaves may be quickly and easily severed from the assembly and simultaneously removed from each other in a single operation by use of the selective separating formations. These selective separating formations include the binding stubs 13 and 14 and the selective grip formation formed by the aperture or notch 15 in the transfer sheet adjacent to the fold line 9 thereof. Thus the assembly is gripped simultaneously by the user at the binding stubs 13 and

14 outside of the weakened severance lines 11 and 12 and at the selective grip formation at the opposite margin of the assembly in line with the aperture 15. Then by exerting a sharp quick pull in opposite directions or by exerting a tearing pull, the record leaves will be severed from the binding along the weakened severance lines 11 and 12, while the transfer leaves will still remain attached thereto. At the same time the transfer leaves will be separated or stripped from interleaved relation with the record leaves 1 and 2 which remain attached together by the weakened fold line 8. The two record leaves can then be separated from each other by severance along the weakened line 8, while the transfer leaves and binding stubs will ordinarily be discarded. It will be noted that the transfer leaves are securely held in transfer position in the assembly by means of the attaching arrangement described and that they have no free end edges adjacent to the free end edges of the record leaves. It will be understood that the assembly leaves are in close contact with each other in actual use but that they are shown in the drawing as being separated so as to improve the disclosure.

In the modified embodiment disclosed in Figs. 4 and 5 of the drawing, the general structure and arrangement are substantially the same as disclosed in Figs. 1, 2 and 3 and corresponding elements are designated by the same reference numerals with the addition of the index *a*. In this embodiment there is no marginal notch in the transfer sheet B corresponding to the notch 15 shown in Fig. 2, but transverse weakened severance lines 16a similar to the lines 16 of Fig. 2 extend substantially across the transfer sheet parallel to and spaced from the fold line 9a thereof so as to form the narrow transverse severable strips or sections 11a corresponding to the severable strips 11 in Fig. 2.

In use the modified embodiment of Figs. 4 and 5 operates and has the advantages substantially as described above in connection with the embodiment of Figs. 1, 2 and 3. But in this second embodiment when it is desired to selectively separate the record and transfer sheets after inscription of the assembly and removal of the ledger sheet C, the assembly will be gripped by the user at one margin adjacent the folds in line with the severable strip 11a and simultaneously gripped at the opposite margin in line with the binding stubs 13a and 14a. Then a quick pull in the opposite directions or a tearing pull will sever the record sheets from the binding stubs along the weakened severance lines 11a, 12a, and at the same time the transfer leaves will be severed along the weakened lines 16a, thus leaving the narrow sections or strips 11a free and unattached whereupon they may be discarded. During this severing operation the record and transfer leaves will be stripped or separated from interleaved relation, whereupon the original and copy record leaves may be severed from each other along the weakened fold line 8a.

It will be noted that the embodiment of Figs. 1, 2 and 3 may be used in the same manner as the embodiment of Figs. 4 and 5 during separation of the assembly leaves; this may be accomplished by gripping the folded assembly margin in line with the narrow sections 11 of the transfer leaves instead of in line with the notch 15 thereof.

In the modified embodiment of the improved assembly, as disclosed in Figs. 6, 7 and 8, the general arrangement of elements is substantially the same as described above in connection with the

other embodiments, and corresponding elements are designated by the same reference numerals with the addition of the index *b*. In this embodiment the single integral folded transfer sheet, corresponding to the transfer sheets B above described, has been replaced by two separate transfer leaves 6b and 7b having adjacent free edges 18 positioned adjacent to the weakened fold line 8b of the record sheet 1b. This arrangement could, of course, be formed by using a single integral transfer sheet and severing it transversely so as to form the two transfer leaves. These transfer leaves 6b and 7b are notched or cut away at their marginal portions as indicated at 15b, so as to provide a selective grip formation similar to that described in connection with Figs. 1, 2 and 3 above. Also, the transfer leaves are formed with transverse weakened severance lines 16b to provide the severable narrow sections 17b. For some purposes the sections 17b may be omitted entirely so the selective grip formation will extend entirely across the assembly.

In use it will be readily understood by those skilled in the art that the embodiment of Figs. 6, 7 and 8 operates substantially as described above in connection with the other embodiments, and that the operative advantages thereof are substantially the same.

While for the purpose of simplicity of disclosure, the different embodiments of the improved manifolding assembly are herein disclosed as including only an original record leaf and one copy record leaf in addition to the ledger sheet, it will be understood that additional transfer copies may be provided for merely by the inclusion in the assembly of additional record and transfer leaves. For example, an additional unit, as shown in Fig. 2 and including record and transfer sheets attached as shown, could be superposed upon the unit shown in Fig. 2 and these units attached together by lines of adhesive similar to the adhesive 3 and similarly positioned. When these two attached units are folded similarly to the assembly shown in Fig. 1 and the ledger sheet C entered as shown, an original record leaf and three copy record leaves would then be supplied in addition to the ledger sheet.

Since certain changes may be made in the above construction and different embodiments of the invention could be made without departing from the scope thereof, it is intended that all matter contained in the above description or shown in the accompanying drawing shall be interpreted as illustrative and not in a limiting sense.

55 The invention having thus been fully described, the following is claimed:

1. In a manifolding assembly, in combination, a plurality of relatively superposed record leaves having attachment with each other along adjacent marginal parts thereof and having opposite marginal parts opposite to said attachment free of attachment with each other, said superposed record leaves having inscription-receiving surfaces respectively positioned for receiving original 60 and transfer inscriptions, and a plurality of transfer leaves in superposed transfer relation with said record leaves and positioned to transfer inscriptions respectively to one of said inscription-receiving surfaces and to the later mentioned 65 additional sheet, said opposite marginal parts of the record leaves being arranged in relatively superposed overlapping relation and each said marginal part having supporting attachment to a different one of said transfer leaves at an adjacent marginal part thereof so as to separately

support said transfer leaves in transfer relation and to provide a passageway for entry of an additional sheet between said opposite marginal parts of the record leaves into transfer relation in the assembly, and to prevent incorrect insertion of said additional sheet, said superposed overlapping marginal parts of the record leaves being arranged to be simultaneously gripped together, and means including said overlapping marginal parts for simultaneously severing said transfer leaves from the assembly and for selectively separating the record and transfer leaves from each other.

2. In a manifolding assembly, in combination, a plurality of relatively superposed record leaves having attachment with each other along adjacent marginal parts thereof and having opposite marginal parts opposite to said attachment free of attachment with each other, a plurality of transfer leaves in superposed transfer relation with said record leaves, said opposite marginal parts of the record leaves being arranged in relatively superposed overlapping relation and each said marginal part having supporting attachment to a different one of said transfer leaves at an adjacent marginal part thereof so as to separately support said transfer leaves in transfer relation and to provide a passageway for entry of an additional sheet between said opposite marginal parts of the record leaves into transfer relation with one of said transfer leaves in the assembly, and to prevent incorrect insertion of said additional sheet, and selective separating formations spaced apart in the assembly and providing for selective separation of said record and transfer leaves, said separating formations including said overlapping marginal parts of the record leaves positioned to be simultaneously gripped together.

3. In a manifolding assembly, in combination, a plurality of relatively superposed record leaves having attachment with each other along adjacent marginal parts thereof and having opposite marginal parts opposite to said attachment free of attachment with each other, a plurality of transfer leaves in superposed transfer relation with said record leaves, each of said opposite marginal parts of the record leaves having supporting attachment to a different one of said transfer leaves at an adjacent marginal part thereof so as to separately support said transfer leaves in transfer relation, and to provide a passageway for entry of an additional sheet between said opposite marginal parts of the record leaves into transfer relation with one of said transfer leaves in the assembly, and to prevent incorrect insertion of said additional sheet, and selective separating formations spaced apart in the assembly and providing for selective separation of said record and transfer leaves, said selective separating formations including weakened severance lines in the record leaves respectively positioned along each of said opposite marginal parts thereof inside of the respective said supporting attachments and forming relatively superposed overlapping binding stubs that can be simultaneously gripped together for effecting said selective separation.

4. In a manifolding assembly, in combination, a plurality of relatively superposed record leaves having attachment with each other along adjacent marginal parts thereof and having opposite marginal parts opposite to said attachment free of attachment with each other, a plurality of transfer leaves in superposed transfer relation

with said record leaves, said opposite marginal parts of the record leaves being arranged in relatively superposed overlapping relation and each said marginal part having supporting attachment to a different one of said transfer leaves at an adjacent marginal part thereof so as to separately support said transfer leaves in transfer relation and to provide a passageway for entry of an additional sheet between said opposite marginal parts of the record leaves into transfer relation with one of said transfer leaves in the assembly, and to prevent incorrect insertion of said additional sheet, and selective separating formations spaced apart in the assembly and providing for selective separation of said record and transfer leaves, one of said selective separating formations including weakened severance lines in the record leaves respectively positioned along each of said opposite marginal parts thereof inside of the respective said supporting attachment and forming relatively superposed overlapping binding stubs that can be simultaneously gripped together for effecting said selective separation, said transfer leaves having their marginal parts opposite to their said supporting attachments free from attachment to the record leaves and formed to provide another of said selective separating formations.

5. In a manifolding assembly, in combination, a plurality of relatively superposed record leaves having attachment with each other along adjacent marginal parts thereof and having opposite marginal parts opposite to said attachment free of attachment with each other, a plurality of transfer leaves in superposed transfer relation with said record leaves, each of said opposite marginal parts of the record leaves having supporting attachment to a different one of said transfer leaves at an adjacent marginal part thereof so as to separately support said transfer leaves in transfer relation and to provide a passageway for entry of an additional sheet between said opposite marginal parts of the record leaves into transfer relation with one of said transfer leaves in the assembly, and to prevent incorrect insertion of said additional sheet, selective separating formations spaced apart in the assembly and providing for selective separation of said record and transfer leaves, one of said selective separating formations including weakened severance lines in the record leaves respectively positioned along each of said opposite marginal parts thereof inside of the respective said supporting attachments and forming relatively superposed overlapping binding stubs that can be simultaneously gripped together for effecting said selective separation, said transfer leaves having their marginal parts opposite to their said supporting attachments free from attachment to the record leaves and free from attachment with each other, said free marginal parts of the transfer leaves having edge portions inset from adjacent edges of the record leaves to provide another of said selective separating formations.

6. In a manifolding assembly, in combination, a plurality of relatively superposed record leaves having attachment with each other along adjacent marginal parts thereof and having opposite marginal parts opposite to said attachment free of attachment with each other, a plurality of transfer leaves in superposed transfer relation with said record leaves, each of said opposite marginal parts of the record leaves having supporting attachment to a different one of said transfer leaves at an adjacent marginal part thereof so

as to separately support said transfer leaves in transfer relation and to provide a passageway for entry of an additional sheet between said opposite marginal parts of the record leaves into transfer relation with one of said transfer leaves in the assembly, and to prevent incorrect insertion of said additional sheet, selective separating formations spaced apart in the assembly and providing for selective separation of said record and transfer leaves, one of said selective separating formations including weakened severance lines in the record leaves respectively positioned along said opposite marginal parts thereof inside of the respective said supporting attachments and forming relatively superposed overlapping binding stubs that can be simultaneously gripped together for effecting said selective separation, and another of said selective separating formations including weakened severance lines in marginal parts of said transfer leaves extending adjacent to a fold therebetween positioned opposite to said supporting attachments thereof and forming detachable folded transfer leaf sections overlapping each other and overlapping adjacent marginal parts of the record leaves.

7. In a manifolding assembly, in combination, a sheet of record material folded intermediate its ends so as to form relatively superposed attached record leaves having marginal portions opposite to the fold of the folded sheet which are free from attachment with each other, each of said free marginal portions of the record leaves having

a weakened severance line forming a severable binding stub, said binding stubs being free from attachment with each other, a plurality of transfer leaves interleaved in transfer relation with said record leaves, a different one of said transfer leaves having supporting attachment at a marginal part thereof with each one of said severable binding stubs but being free of attachment with another said binding stub, said severable binding stubs being in overlapping superposed relation whereby they can be simultaneously gripped together to provide a separating formation for selective separation of the record and transfer leaves, the margins of said transfer leaves opposite to said supporting attachments thereof being positioned adjacent to said fold of the folded sheet, and a selective separating formation for the record and transfer leaves adjacent to said fold.
